UNITED STATES PATENT OFFICE.

GEORGE L. PIERCE, OF BROOKLYN, NEW YORK.

SHOE.

1,039,437.

Specification of Letters Patent. Patented Sept. 24, 1912.

Application filed February 17, 1911. Serial No. 609,229.

To all whom it may concern:

Be it known that I, GEORGE L. PIERCE, a citizen of the United States, residing at Brooklyn, in the county of Kings and State 5 of New York, have invented certain new and useful Improvements in Shoes, of which the following is a specification.

My present invention relates to shoes having rubber soles and has for its object improving means for securing the rubber sole to the shoe whereby the sole cannot tear away either in whole or in part when subjected to use and wear.

My invention is especially an improvement on the well-known way of securing rubber soles to shoes by marginal stitches passing through the thickness of the rubber sole. Such shoes are unsatisfactory in use because the marginal portions of the soft 20 rubber, an inherently weak material, soon tear away from the stitches. My present invention remedies this defect and its importance will be realized from the fact that, in spite of the great quantities used of this 25 type of shoe, nothing practical has heretofore been found to remedy the defect in question.

This and the other merits and advantages of my present improvement will be apparent to those skilled in the art from an understanding of the following description in connection with the drawings which show one form of shoe embodying my improvement.

Figure 1 is a side elevation of such a shoe, part of the upper being cut away to reveal internal structure; Fig. 2 is a cross sectional view, partly in elevation, on the line 2—2 in Fig. 1 looking in the direction 40 of the arrow; and Fig. 3 is a partial view of Fig. 2 but showing a modification.

I will now describe the devices of the drawings, reserving it to the claims to point out the novel features constituting my improvement and to indicate the scope of my invention, it being understood that the claims will be given due range of equivalents.

In the drawings, 1 is the inner sole of the 50 shoe having marginal ridges 2 on its underside.

3 is the upper or vamp portion of the shoe; 4 is the welt; 5 are the stitches by which the bottom edges of the upper 3 and 55 the adjacent welt 4 are sewed to the ridges 2 of the inner sole.

6 is the rubber sole and 7 is canvas vulcanized to the upper face of the rubber sole and having edge or marginal portions 7^a projecting beyond the rubber sole. Instead of canvas, other suitable fabrics or materials may be substituted that have suitable strength and can be vulcanized or secured permanently to the rubber sole, e. g. by non-marginal stitching or otherwise. 65 The canvas piece preferably has the same shape as the rubber sole but is sufficiently larger to have the described projecting margins 7^a.

9 is any suitable filling material between 70 the inner sole and the rubber sole. Finally, the rubber sole is secured to the shoe by stitches 8 sewed through the margins 7^a of the canvas and the welt 4. For this purpose, the outer edge of the welt extends sufficiently beyond the edge of the rubber sole. 75 This secures the rubber sole to the shoe without permitting it to tear away. To finish the shoe, the projecting margin of the canvas can be cemented snugly against the 80 edge of the rubber sole, thereby concealing the stitches 8.

As another method of securing the canvas margin 7^a, it may be folded back on itself as shown in Fig. 3, whereupon the 85 stitches 8 will be inserted. This also gives a neat finish and great strength because the stitches now pass through a double thickness of the canvas.

Of course, it will be understood that the 90 invention does not relate to the particular make-up of the shoe to which my improvement is shown as being applied, since that may vary, but it does relate to the rubber sole attaching means combination. In short, 95 the improvement is applicable not only to "welted" but also to "turned" shoes and to "McKayed" shoes, etc.

It will be understood that the term "rubber-sole" used herein does not mean that 100 the sole must necessarily be continuous from heel to toe, since it may consist merely of a tap secured on the portion of shoe according to my invention, or may consist only of a heel, or of a heel and tap joined by a 105 flexible shank portion. Further, the term "rubber" includes any equivalent thereof for the purposes of and within the spirit of this invention.

Having thus described my invention, 110 what I claim is.

1. In a shoe, an upper, a sole comprising

- a rubber body and a fabric backing permanently secured to the upper face of the body and having integral marginal portions projecting beyond the edges of said body, and
- 5 means passing through the projecting marginal flanges of the fabric backing only, directly adjacent to the edges of the rubber body for securing the sole to the upper.
2. In combination, a shoe, a rubber sole, and means for securing the rubber sole to the shoe comprising canvas material vulcan-
- 10

ized to the top of the rubber sole and having a folded margin projecting beyond the sole, and stitching securing said folded margin to the shoe.

15

In testimony whereof I affix my signature in presence of two witnesses.

GEORGE L. PIERCE.
